CARBURETOR ATTACHMENT FOR MOTOR VEHICLES

Aladar Csecs, 26 Holly Place, Stamford, Conn.

Filed May 16, 1958, Ser. No. 735,722

6 Claims. (Cl. 261—51)

This invention relates to a carburetor attachment in motor vehicles and it has particular relation to an auxiliary apparatus adapted to be used in motor cars or the like, in order to reduce gasoline consumption.

This auxiliary apparatus of this invention is designed to cut down the gas consumption whenever the carburetor throttle is suddenly closed. When this is done, the power of the engine is not needed for a while but the inertia of the running car forces the engine to make additional turns thus sucking in more gas than needed at this moment. Although this condition lasts only for a few seconds, yet when it frequently occurs, e.g. in city traffic, the amount of wasted gasoline accumulates considerably.

Operation of this auxiliary device is based on sudden closure of the main jet whenever the throttle is closed, leaving only the idle orifice partially open. However the idling jet channel passes the gasoline to the idling orifice undisturbed because the auxiliary check valve has no connection whatsoever to the idling channel.

The appended drawings illustrate by way of example, and without limitation, some specific embodiments of and best ways for carrying out the invention.

In the drawings, Fig. 1 illustrates in sectional view part of the carburetor, which houses the device of the invention; Fig. 2 illustrates operation of the diaphragm used according to the invention; Fig. 3 serves to illustrate operation of the invention; Figure 4 illustrates a carburetor with a built-in device according to the invention, in sectional view.

Referring now to the drawings in detail, Fig. 1 shows the cross section of the part of the carburetor that houses the invention. As shown in this figure, the butterfly valve (throttle) 1 is in a position in which it keeps the engine idling. Closing or opening the orifice 9 regulates this idling speed, allowing less or more combustible mixture to the intake manifold. The quality of the mixture (lean or rich) may be changed by turning the adjusting screw 11 and the needle valve 10 of the carburetor. These parts work in the same way as in any conventional carburetor.

The idling channel starts at the opening 22, gets a little air at 21 for "emulsion" and then ends at the two orifices 9 and 10. The liquid gasoline passes through this channel without any obstacle. When the throttle is sufficiently opened, the idle jet ceases to operate but the rush of air from the barrel 12, passing through the venturi 13 draws the gasoline vapor from the main jet 16 thus supplying the combustible gas for normal drive through the main nozzle 14, the gasoline enters the main jet through the compensating passage 17.

The float chamber 15 keeps the constant liquid level as usual. The float itself, the needle valve and the gasoline supply line are not shown for the sake of clearness.

As clearly shown in Fig. 1, when the throttle is in idle position, rod 4 holds the piston valve 5 between the ports of pipes 7 and 8 thus completely blocking the air passage from the vacuum pump 35 through the duct

2

formed by pipes 7 and 8. No matter how strong the suction in this connecting tube and the vacuum pump is, it is unable to draw air from pipe 8 and consequently unable to create even little vacuum above the diaphragm 20.

5 The diaphragm flexes downward by its own elastic tension, pushes the valve stem 19 and the check valve 18 down, the latter closes the port in the main jet channel 16 and thus stops the flow of liquid gasoline to the main nozzle. As soon as the driver "steps on the gas" rod 3 moves 10 to the left, turns arm 2 and more or less opens the throttle 1.

Simultaneously rod 4 also moves to the left and pulls the piston valve 5 from its position between the two air-passage ports, 7 and 8.

The withdrawn position of this piston is shown in Fig. 3. In the moment when the piston valve 5' is moved away from the closing position, the ports of pipes 7' and 8' open and thus secure the air passage from diaphragm 20 to the vacuum pump 35. Under the sucking 20 action of the motor and the vacuum pump, the air rushes in the direction of arrows, whereby vacuum develops above the diaphragm and the latter flexes upward under the atmospheric pressure under the disc. Thereby check valve 18 is lifted and the normal flow of gasoline 25 through opening 17 to the main nozzle 14 is restored. Then the usual function takes place like in any conventional carburetor. The air rushes downward through "air horn" 12 and the gasoline sprays out of the main nozzle 14 supplying the desired explosive mixture. 30 Diaphragm 20' is kept up while the car runs with open throttle as shown in Fig. 2.

35 The operation of the diaphragm under the effect of vacuum is shown in Fig. 2. The check valve 18' opens sufficiently in order to let the gasoline flow in accordance with the engine speed and power.

When the driver closes the throttle again, either with the intention to stop the car or using the engine as a compression brake on a steep down hill, the piston valve 40 5' closes the ports, the vacuum above the diaphragm 20' disappears, whereby valve 18' prevents passage of superfluous gasoline to the air horn, by closing the valve seat in the main channel.

45 However, the idling jet still operates and prevents the engine from stalling when the car stops and the clutch is disengaged.

The diaphragm must be soft enough to react even to a slight vacuum; otherwise the engine stalls, sputters or backfires while "starving for gas."

There must be a turnbuckle 23 on the rod 4 to adjust 50 the length of this rod to place the piston valve 5 in its proper position. Ball joint 24 secures the linear motion of the piston valve.

55 The narrow channel 6 gives way to the compressed air to escape from the cylinder when the piston valve moves to the closing position. Another channel 33 is needed to restore the atmospheric pressure above diaphragm 20 when the throttle is suddenly closed.

60 There must be a compensating hole 25 under the diaphragm 20 to restore the atmospheric pressure when the vacuum is not needed e.g. when the throttle is closed; the escape of air through this opening also results in quick closing of the check valve 18, thus preventing the waste of gasoline.

65 While Fig. 1 shows a conventional carburetor with the gas-saving apparatus of the invention as a separate attachment, Fig. 4 shows a specially constructed carburetor in which the gas-saving apparatus is a built-in part, combined with the otherwise standard carburetor.

70 The working principle is thereby the same as in the arrangement shown in Figs. 1, 2 and 3. The diaphragm 20 operates by the effect of vacuum, created by the suction in the vacuum pump, regulated by piston valve 5

whereby check valve 18 closes the opening of the main jet 16, 14 whenever the throttle 1 is closed and the vacuum is eliminated.

The built in arrangement requires certain additional parts to make the check valve adjustable after the carburetor has been completely assembled. Furthermore the vacuum regulating piston valve should be fastened on to the carburetor itself instead of the dashboard.

The diaphragm 20 is mounted on the float chamber of the carburetor by screws 26, secured by lock washer.

The sheath 28 is fastened to the center of the diaphragm by lock-nuts. When the diaphragm is thus fastened, the sheath or sleeve 28 must slide on the valve stem 19 in a "snug fit." While the diaphragm is in its natural shape, the valve stem should be in a position in which check valve 18 rests on its seat, which means that the check valve closes the main jet when the diaphragm is in its lowest position. Then the pipe plug 27 is removed, adjusting screw 29 is tightened and the right position of the valve 18 is thus secured. The pipe plug 28 can be then inserted in its original position.

Such adjustment may be needed once in a while whenever the diaphragm changes its shape or its elasticity, since check valve 18 must always rest on its seat when the gas is taken off and the engine idles.

Cylinder 32 that houses the vacuum regulating piston valve 5 is fastened to the flanges of the carburetor float chamber. For this purpose these flanges are cast with "bosses" 30 whose smooth surfaces are held against the flanges of the cylinder 32. Two lock-washer secured bolts 31 hold the cylinder firmly on the bosses.

In Fig. 4 the arm 2 is located on this side of the carburetor and rod 4 is on the opposite side; cylinder 32 is placed on the opposite side (beyond the float chamber) but shown in cross-section for the sake of clearness.

To raise the diaphragm 20 a relatively high degree of vacuum is necessary. Although the intake manifold keeps up a certain degree of vacuum (air pressure difference between the air horn 13 and the outside atmosphere), this is inadequate to open the check valve 18 especially during the operation of the self starter. The electric motor turns the engine too slowly to create sufficient vacuum in the manifold.

In order to safely secure operativeness under variable circumstances, a "vacuum booster" should be added to increase the vacuum above the diaphragm 20 while the engine runs even with slightly open throttle.

Most automobile engines are at present equipped with a "combination of fuel and vacuum pump." Both are operated by the camshaft as soon as the engine begins to turn. The outlines of this combination pump are shown in Fig. 1 and Fig. 4. The lower cylinder 34 is the fuel pump to deliver the gasoline from the tank to the carburetor float chamber. This pump does not play any part in this invention. The upper cylinder 35 is the vacuum pump that otherwise operates the windshield wiper, certain valves in connection with the automatic transmission, etc. Both pumps are operated by cam 36 and lever 37 that move the leather diaphragms up and down in accordance with the revolution of the camshaft.

At the throttle opening the piston valve 5 also opens the air passage. The pump 35 sucks the air that flows in the direction of arrows. It passes through pipes 8, 7 to the pump chamber from where (38) it is discharged to the intake manifold. The cooperation of the manifold and pump greatly increases the air pressure difference between the lower and upper side of the diaphragm 20 thus giving it enough force to open the check valve 18.

Reference is made to my copending patent application filed in my name under Serial No. 719,338 on March 5, 1958, now abandoned, of which this is a continuation-in-part.

What is claimed is:

1. In connection with a vehicle motor carburetor having a throttle for regulation of the motor's gas intake and having a fuel valve, a fuel saving device comprising an air duct, sucking means at one end of said duct, an air chamber at the other duct end, a diaphragm forming a hermetically closing wall of said air chamber, having one side facing said air chamber and having another side exposed to atmospheric pressure whereby the central part of said diaphragm moves when suction reaches said air chamber, said central part being affixed to said fuel valve in a position in which said fuel valve is closed when said diaphragm is relaxed and is opened when said diaphragm moves under the influence of suction in said air chamber, and means operatively connected with said throttle interrupting said duct when said throttle is closed and opening said duct when said throttle is opened, whereby suction will reach said air chamber and said fuel valve will be opened only when said throttle is opened.
2. A device according to claim 1 in which said sucking means comprises a vacuum pump.
3. A device according to claim 1 in which said duct-interrupting means comprise a cylinder having a main bore and a crossbore forming an intermediate part of said duct, and a piston movable in said main bore across said crossbore.
4. A device according to claim 1 in which said duct-interrupting means comprise a cylinder having a main bore closed at one end and open at the other end, having a crossbore forming an intermediate part of said duct, having a channel connecting said closed bore end with the part of said crossbore nearer to said sucking means, and having another channel connecting a median part of said main bore with the part of said crossbore which is nearer to said air chamber, and a piston movable in said main bore between a position in which said piston closes said crossbore and opens said other channel and a position in which said piston opens said crossbore and closes said other channel.
5. In connection with a vehicle motor carburetor having a throttle for regulation of the motor's gas intake and having a fuel valve, a fuel saving device comprising an air duct, sucking means at one end of said duct, an air chamber at the other duct end, a diaphragm dividing said air chamber into two hermetically separated spaces, one communicating with said duct and the other with the outer atmosphere whereby the central part of said diaphragm moves when suction reaches said first mentioned chamber space, said central part being affixed to said fuel valve in a position in which said fuel valve is closed when said diaphragm is relaxed and is opened when said diaphragm moves under the influence of suction in said first mentioned chamber space and means operatively connected with said throttle interrupting said duct when said throttle is closed and opening said duct when said throttle is opened, whereby suction will reach said first mentioned chamber space and said fuel valve will be opened only when said throttle is opened.
6. A device according to claim 5 to be used in connection with a vehicle motor carburetor which further has a float chamber, said other air chamber space forming an upper part of said float chamber whereby said other air chamber space communicates with the outer atmosphere through said float chamber.
